SEAT CONSTRUCTION

Application filed March 6, 1931. Serial No. 520,509.

This invention relates to seat constructions, and has for an object the provision of a novel design of seat, which, while being capable of substantially universal application, affords particular convenience for use in restaurants, ice-cream parlors, and the like.

A more detailed object is the provision of a seat construction wherein the seat may be pulled forward when occupied, but which may be pushed back into retracted position to afford greater convenience to the person getting into or out of the seat.

Another object is to provide an adjustable seat as described, in which the back also is adjustable, and is connected to the seat itself, so that the back is moved simultaneously with movement of the seat.

A further object is to provide an adjustable seat construction as described, which is of the knockdown type, permitting shipping and/or storage of the entire seat construction within a relatively small space, and also permitting facile assembly thereof when desired.

25 A still further object is to provide a seat construction having the above described characteristics, which is of unusually simple and rugged design, and which may be produced at relatively low cost.

30 The invention possesses other objects and advantageous features, some of which, with those enumerated, will be set forth in the following description of the invention's particular embodiment which is illustrated in 35 the drawing accompanying and forming a part of the specification.

Referring to the drawing:

Fig. 1 is a perspective view of an assembled seat construction having the principles of 40 the present invention incorporated therewith.

Fig. 2 is a vertical transverse sectional view.

Fig. 3 is a perspective view of the frame which forms a portion of the seat construction of the present invention, and the associated portions of the end walls showing the cleats thereon, whereby the frame is mounted in operative position. Portions of the end walls are broken away to reduce the size of 50 the figure.

My improved seat construction comprises a pair of spaced end walls 6 and 7, each of which comprises an enlarged base portion 8 and a back supporting portion 10. Whereas it is entirely within the scope of the present invention to arrange my improved seat construction as a single seat, Fig. 1 illustrates the invention as being incorporated in a structure providing seats for four persons, there being two seats upon each side of the 55 device. Accordingly, the enlarged base portion 8 of each end wall 6, 7 projects beyond both edges of the back supporting portion 10, as clearly illustrated upon Figs. 1 and 2.

Each of the end walls 6, 7 has a cleat 9 60 rigidly, and preferably permanently, secured to the inner face thereof. These cleats 9 are at the same elevation above the lower edges 11 of their respective end walls 6, 7. Preferably, each end of each cleat 9 is provided with a tenon 12, whereby a frame, which is indicated in its entirety at 13, may easily be mounted thereupon. This frame 65 comprises bars 14 and 15 retained in spaced parallel relationship by a transversely extending bar 16 and a transversely extending board or seat guide member 17, upon each side of the bar 16 and parallel thereto. Each end of each of the bars 14 and 15 is provided with a mortise 18 adapted to receive one of the 70 tenons 12, whereby the frame 13 may substantially instantaneously be mounted upon both cleats 9, as will readily be understood.

The two end walls 6 and 7 are rigidly, but demountably joined by a bar 21 which is 75 secured thereto by any suitable releasable fastening means, such as conventional wood screws 22. I preferably employ a second bar 23 extending between the two end walls 6 and 7 adjacent their lower edges and similarly secured thereto. The parts are so proportioned and arranged that when the end walls 6 and 7 are fastened to the horizontal bars 21 and 23, they will be so spaced that the bars 14 and 15 are rigidly clamped between the end walls 6 and 7 and engaged by the tenons 12 of the cleats 9, so as to impart 80 rigidity to the frame 13, which is thus supported horizontally between the two end walls 6 and 7. If desired, conventional corner 85 90 95 100

plates 24 may then be mounted in such a manner as to impart rigidity to each intersection of the bars 14 and 15 with the cleats 9.

A rod 26 is rigidly secured to, and extends 5 between the two end walls 6 and 7, this rod extending horizontally and closely below the upper horizontal bar 21. A plurality of seat backs 27 are suspended by being pivotally mounted adjacent their upper edges upon the 10 rod 26. For this purpose each of the backs 27 is provided with preferably a pair of hook-shaped strips 28 which engage the rod 26. A seat 29 is associated with each of the backs 27, the after edge of the seat being pivoted 15 adjacent the lower edge of the back 27 by means of any suitable hinge construction 31. However, instead of supporting the weight of the seat 29 and that of a person seated thereupon by means of the back 27, this weight is 20 supported by the horizontal frame 13, inasmuch as all the seats 29 are supported thereupon, the association between the seats 29 and the frame 13, however, being such that each 25 seat may be adjusted substantially in a horizontal plane, so as to vary the distance that the seat extends beyond the forward or outer edge of the frame 13. In Fig. 2 the seat illustrated at the left hand side of the figure is shown as being fully retracted, whereas the 30 seat illustrated on the right hand side of the figure is shown in extended position.

To facilitate this adjustment of the seat, each seat is supported upon the frame 13 through the expedient of rollers 32, preferably four rollers being provided for each of the seats, two adjacent each of the lateral edges thereof. The rollers 32 adjacent one 35 of the lateral edges of each seat 29 rest upon one of the cleats 9, whereas the other rollers 40 of that seat rest upon the central bar 16 of the frame 13.

When the seats are in retracted position, the rollers 32 thereof which are adjacent their 45 after edges engage within depressed portions 33 which are provided in the central bar 16 and in the cleats 9. Each of these portions 33 provides inclined faces sloping upwards and toward the outer edges of the frame 13, i. e., they slope upwards and from the 50 central portion thereof, the purpose of this arrangement being to cause the after edge of each seat 29 to be raised slightly as the seat is pulled forward, thus compensating for the slight amount of upward motion of the seat back 27, which is caused by the arcuate motion of the back when pulled forward. That 55 portion of the associated cleat 9 and the central bar 16 which the forward rollers 32 engage, is preferably perfectly horizontal, except for the fact that notches 34 are provided in such position that each of the forward rollers 32 will drop thereinto when the seat 29 reaches approximately its forward extreme of adjustment.

65 To prevent inadvertent displacement of

the seats 29 by pulling them too far forward, and also to permit clamping each or all of the seats 29 in selected position, each seat is provided with a bolt 36 which extends rigidly downward therefrom through an elongated 70 slot 37 in the associated horizontal board 17 of the frame 13. The length of these slots limits the extent of movement of the seats 29; and if it is desired to lock the seats in selected position the nuts 38, one of which is 75 threaded onto each of the bolts 36 below the board 17, may be tightened.

From the above described construction, it becomes apparent that the device of the present invention will be of utility in restaurants, 80 ice-cream parlors, breakfast nooks, and similar installations where a rigidly positioned table is employed, and where permanently mounted seat constructions are associated with the table or tables. When employing the conventional type of seat constructions 85 difficulty was frequently encountered by persons getting into the seats, because of the relatively small space which is left between the table and the seat constructions. If sufficient space is left to permit facile ingress and egress to and from the seats, respectively, it 90 is found that the seats are positioned so far from the edge of the table that considerable inconvenience results; and if the seat construction is positioned close enough to the 95 table to permit persons to use the table comfortably when seated, difficulty is encountered in getting into and out of the seats. This 100 disadvantage is overcome by means of the 105 construction hereinabove described, because when the seats are not occupied they may be pushed back into retracted position, as illustrated upon the left hand side of Fig. 2. This 110 will permit a person to get into the seat very 115 easily, whereupon he may easily pull the seat 29 forward until its forward rollers 32 drop into their associated notches 34, whereupon it will be found that the occupant of the seat is positioned close enough to the table to use 120 the table for any desired purpose with perfect comfort. When it is desired to leave the seat 29, the occupant has only to arise, and it will be found that the backs of his knees will strike the forward edge of the seat 29, causing the forward rollers 32 to be lifted out of the notches 34, and the entire seat 29 and the back 27 to be pushed back into retracted position.

A transversely extending partition 41 extends between the two end walls 6 and 7 in such position that it limits the motion of the seats 29 and backs 27 when being retracted. I preferably employ another partition 42 between each pair of seats 29 and their associated backs 27 upon each side of the seat construction, thereby preventing the possibility of clothing or other articles being caught between adjacent edges of the seat backs 27 130

when one of the backs is pulled forward and the other is in retracted position.

If desired, a spring 43 may be so associated with each of the seats that whenever an occupant of the seat rises, the spring will raise the forward edge of the seat sufficiently to remove the associated roller 32 from the notch. The seat 29 and its back 27 will then move to retracted position by gravity, because the after roller 32 of the seat rests upon the inclined surface 33.

It is to be understood that the details of the invention as herein disclosed, are subject to alteration within the spirit or scope 15 of the appended claims.

I claim:

1. A seat construction comprising side supporting members, means connecting the side supporting members adjacent the top thereof, a back hingedly connected adjacent its top to said connecting means, rails supported upon said side supporting members, each rail having a substantially horizontal forward portion and a downwardly and rearwardly sloping rear portion, a seat, forward and rear rollers on the under side of the seat 4 supporting the seat upon the rails, the forward rollers resting normally on the horizontal portions of the rails and the rear rollers normally resting on the sloping portions of the rails, and means forming a hinged connection between the bottom of the back and the seat adjacent the rear edge of the seat.

35 2. A seat construction comprising side supporting members, means connecting the side supporting members adjacent the top thereof, a back hingedly connected adjacent its top to said connecting means, rails supported upon said side supporting members, each rail having a substantially horizontal forward portion and a downwardly and rearwardly sloping rear portion, a seat, forward and rear rollers on the under side of the seat 45 for supporting the seat upon the rails, the forward rollers resting normally on the horizontal portions of the rails and the rear rollers normally resting on the sloping portions of the rails, means forming a hinged 50 connection between the bottom of the back and the seat adjacent the rear edge of the seat, and means connected to the side members on the inner sides thereof engageable by the back of the back to limit rearward 55 movement of the seat and back.

3. A seat construction comprising side supporting members, means connecting the side supporting members adjacent the top thereof, a back hingedly connected adjacent its 60 top to said connecting means, rails supported upon said side supporting members, each rail having a substantially horizontal forward portion and a downwardly and rearwardly sloping rear portion, a seat, forward and rear rollers on the under side of the seat

for supporting the seat upon the rails, the forward rollers resting normally on the horizontal portions of the rails and the rear rollers normally resting on the sloping portions of the rails, and means forming a hinged connection between the bottom of the back and the seat adjacent the rear edge of the seat, there being notches formed in the horizontal portions of the rails adapted to receive the forward rollers to hold the seat 75 in foremost position.

4. A seat construction comprising side supporting members, means connecting the side supporting members adjacent the top thereof, a back hingedly connected adjacent its top to said connecting means, rails supported upon said side supporting members, each rail having a substantially horizontal forward portion and a downwardly and rearwardly sloping rear portion, a seat, forward and rear rollers on the under side of the seat for supporting the seat upon the rails, the forward rollers resting normally on the horizontal portions of the rails and the rear rollers normally resting on the sloping portions of the rails, means forming a hinged connection between the bottom of the back and the seat adjacent the rear edge of the seat, there being notches formed in the horizontal portions of the rails adapted to receive the forward rollers to hold the seat 80 in foremost position.

5. A seat construction comprising side supporting members, means connecting the side supporting members adjacent the top thereof, a back hingedly connected adjacent its top to said connecting means, a frame provided with rails supported upon said side supporting members, each rail having a substantially horizontal forward portion and a downwardly and rearwardly sloping rear portion, a seat, forward and rear rollers on the under side of the seat for supporting the seat upon the rails, the forward rollers resting normally on the horizontal portions of the rails and the rear rollers normally resting on the sloping portions of the rails, and means forming a hinged connection between the bottom of the back and the seat adjacent the rear edge of the seat, seat guide members on said frame and provided with slots, and bolts secured to the underside of the seat and extending downwardly through the slots, said bolts having nuts which on tightening against the slotted guide members will lock the seat against movement on the rails.

In testimony whereof I have signed my name to this specification.

LEVON H. GAZARIAN.
